United States Patent Office

Des. 194,889
Patented Mar. 26, 1963

194,889

JAR

John F. Dubbs, Lancaster, Pa., assignor to Armstrong Cork Company, Lancaster, Pa., a corporation of Pennsylvania

Filed Apr. 9, 1962, Ser. No. 69,648

Term of patent 14 years

(Cl. D58—25)

The view is a side elevation of a jar showing my new design.

The dominant features of my design reside in the portions shown in full lines.

I claim:

The ornamental design for a jar, substantially as shown and described.
